UNITED STATES PATENT OFFICE.

SAMUEL N. HALL, OF LOS ANGELES, CALIFORNIA, ASSIGNOR TO MAHLON E. LAYNE,
OF LOS ANGELES, CALIFORNIA.

CLUTCH DEVICE FOR PUMPS.

Application filed September 8, 1920. Serial No. 408,942.

To all whom it may concern:

Be it known that I, SAMUEL N. HALL, a citizen of the United States, residing at Los Angeles, in the county of Los Angeles and State of California, have invented certain new and useful Improvements in Clutch Devices for Pumps, of which the following is a specification.

The invention relates to a clutch device for well or pump mechanism, involving the use of a centrifugal or rotary pump with power transmission and discharge means extending upwardly to the surface of the ground. It has for its primary object the provision of improved means for preventing the backward movement of the pump impellers and the driving mechanism after the pump is stopped due to the return to the well of the column of water in the discharge casing, as such backward movement tends to loosen the screw connections in the pump shaft. A further object of the invention is to provide means of the character specified which are of cheap simple construction, operating noiselessly on the forward movement of the pump and not subject to wear during such forward movement. Certain embodiments of the invention are illustrated in the accompanying drawings, wherein—

Figure 1 is a partial vertical section and partial side elevation of a pump equipped with the invention. Fig. 2 is an enlarged plan view of the lower clutch members shown in Fig. 3. Fig. 3 is an enlarged vertical section through the clutch device employed. Fig. 4 is a partial vertical section on the line IV—IV of Fig. 2. And Figs. 5 and 6 are vertical sections through modified forms of clutch devices.

The invention is designed to provide a simple and effective means for preventing the backward movement of the pump impellers with the shaft and driving mechanism after the pump has stopped. Under these conditions and with a relatively deep well the water flows backward through the discharge casing rotating the impellers with an increasing velocity until the level of the water in the discharge casing reaches that in the well. The impellers then immediately act as a powerful brake tending to stop the backward rotation of the shaft. When the shaft is driven by an electric motor, the inertia of the rotating motor parts is

very considerable and reaches its maximum at the time the level of the water in the discharge casing arrives at the level of the water in the well so that at this time when the braking effect of the water upon the impellers is applied a powerful twist is exerted upon the drive shaft which twist tends to loosen and unscrew the sections of the shaft.

The present invention is designed to overcome this difficulty, and briefly stated involves the use of an automatic clutch which will permit the forward movement of the drive shaft without any interference therewith but will lock and prevent any backward movement as soon as the forward rotation of the shaft is stopped.

Referring now to the drawings, 1 is the casing of a rotary or centrifugal pump from which the discharge casing 2 leads upward to the platform 3 at the surface of the well. For convenience in illustration the casing and other parts inside such casing are broken away below the platform, but it will be understood that the distance which ordinarily separates the pump 1 and the platform 3 is relatively great, running anywhere from 50 feet up to several hundred feet so that the column of water in the casing 2 is of very considerable height and in the ordinary pump the backward movement of such column of water after the pump stops will give the pump impeller and the drive shaft a rapid movement of rotation. The impellers 4 are carried by the drive shaft 5 and such drive shaft is surrounded by shaft casing 6, extending to the platform 3. The shaft 5 is made up of a plurality of sections, the bottom only of one of such sections being shown, and these sections are connected by the ordinary sleeve couplings so arranged that the forward movement of the shaft tends to tighten them, but the backward movement tends to loosen them resulting in the difficulty herefore referred to.

Referring to the upper portion of the construction in Fig. 1, 7 is the motor provided with a stub shaft 8 coupled at 9 to the upper clutch member 10, which forms a part of the improvement to which this invention is particularly directed. The upper clutch member 10 is keyed to the pump shaft 5 and opposes a lower clutch member 11, which is fixed in position by being screw

threaded into the casting 12, as illustrated in Fig. 1.

The particular construction of the clutch will be seen by reference to Figs. 2, 3 and 4. The lower clutch member is provided with four recesses 13 each of which has its forward side 14 inclined as indicated in Fig. 4 and its rear side upright as indicated at 15 in Fig. 4. The upper clutch member is provided with recesses 16 opposing the recesses in the lower member, such recesses having outwardly directed portions 17. When the shaft 5 is rotated forwardly the balls 15 are rolled along the sides 14 of the recess in the lower clutch member and centrifugal force then carries them to the positions indicated in dotted lines in Fig. 3, at which time they are entirely out of contact with the clutch member 11. As soon as the rotation of the shaft stops, the balls drop by gravity to the positions indicated in full lines in Fig. 3, and when in this position they prevent the backward movement of the shaft due to the fact that the rear walls of the recesses in the lower clutch member are upright as indicated at 15. It will be seen that the clutch is automatic in action the balls being moved to inoperative position by centrifugal force when the shaft is rotated forwardly, and that such balls move back automatically to locking position as soon as the forward rotation of the shaft stops. The device, therefore, requires no attention and there is substantially no wear upon it since the balls are out of wearing contact during the forward movement of the shaft. The clutch device may be conveniently installed at the location indicated in Fig. 1, but it will be understood that this clutch might be placed anywhere along the line of the shaft 5 wherever it is convenient to place two clutch members.

Various other arrangements of clutches might be applied for accomplishing the same function, only two of a large number of means being shown in Figs. 5 and 6. In Fig. 5 the upper clutch member 18, which is keyed to the shaft 5, is provided with an inclined recess 19 which opposes a recess 20 in the lower clutch member 21, such latter recess having its front wall inclined and its rear wall straight corresponding to the construction illustrated in Fig. 4. The forward rotation of the shaft carries the balls 22 out of the recess in the clutch member 21 and centrifugal force holds the balls in the upper ends of the recess 19 as long as the shaft rotates forwardly, the balls then dropping back to position as indicated.

In the construction of Fig. 6 the pins 23 are mounted in the upper clutch member 24, the recess 25 in the lower clutch member 26 being similar in construction to those of Figs. 2, 3, and 4. The slots or recesses 26 which carry the pins 23 are so formed that

when the pins have been moved upwardly room is provided for their outward movement also so that they assume the position illustrated, at which time the neck of the pin is engaged as indicated at 27 and as long as 70 the rotation of the shaft continues, the pin is held against downward movement. Various other embodiments of the clutch for carrying out the invention will be apparent to those skilled in the art. 75

What I claim is:

1. The combination with a vertical driven shaft, of a clutch disc or plate secured to the shaft so as to rotate therewith and having passages extending from its lower horizontal face upward, a fixed clutch member with its upper face in opposition to the lower face of said plate and provided on such face with grooves of increasing depth in opposition to said passages, and wedging members 80 lying partly in the passages and partly in the grooves and preventing backward movement of said plate and the shaft, but adapted to be moved up into said passages so as to clear the fixed member when said plate is moved forwardly and to be held in such upper position by centrifugal force. 85

2. The combination with a vertical driven shaft, of a clutch disc or plate secured to the shaft so as to rotate therewith and having 90 passages extending from its lower horizontal face, upward, a fixed clutch member with its upper face in opposition to the lower face of said plate and provided on such face with grooves of increasing depth 100 in opposition to said passages, and wedging balls lying partly in the passages and partly in the grooves and preventing backward movement of said plate and the shaft, but adapted to be moved up into said passages 105 so as to clear the fixed member when said plate is moved forwardly and to be held in such upper position by centrifugal force. 110

3. The combination with a vertical driven shaft of a clutch disc or plate secured to the shaft so as to rotate therewith and having 115 passages extending from its lower horizontal face upwardly and outwardly, a fixed clutch member with its upper face opposite the lower face of said plate, and provided in such face with grooves of increasing depth in opposition to said passages, wedging balls lying partly in said passages and partly in said grooves and preventing backward movement of said plate and the shaft, 120 but adapted to be moved up into said passages so as to clear said member when said plate is moved forwardly and to be held in such upper position by centrifugal force. 125

4. In combination, a vertical drive shaft 130 and means for driving the shaft, of means for preventing the backward movement of the shaft comprising a lower fixed clutch member provided with a recess in its upper face with one side upright and the other in-

- clined, an opposing upper clutch member rotatable with the shaft and provided with a recess opposite the first recess and extending upwardly and outwardly, and a clutch 5 element lying in the recesses and preventing backward movement of the upper member, but adapted to move upwardly on the said inclined side of the first recess, and outwardly in the second recess by centrifugal 10 force when the shaft is rotated forwardly.
5. In combination, a vertical drive shaft and means for driving the shaft, of means for preventing the backward movement of the shaft comprising a lower fixed clutch member provided with a recess in its upper 15 face with one side upright and the other inclined, an opposing upper clutch member rotatable with the shaft and provided with a recess opposite the first recess and extending upwardly and outwardly, and a clutch 20 ball lying in the recesses and preventing backward movement of the upper member, but adapted to be moved upwardly on said inclined side of the recess in the lower member and outwardly in the recess in upper 25 member by centrifugal force when the shaft is rotated forwardly.

S. N. HALL.
